[57] CLAIM

The ornamental design for a battery adapter to provide proper fit into battery tray, as shown and described.

DESCRIPTION

FIG. 1 is a perspective view of the battery adapter to provide proper fit into battery tray;
FIG. 2 is a top plan view thereof;
FIG. 3 is a bottom plan thereof;
FIG. 4 is a front elevation view thereof, the rear elevation view being a mirror image; and,
FIG. 5 is a right side elevation view thereof, the opposite side being a mirror image.

FIG.1

FIG.2

FIG. 3

FIG. 4

FIG. 5
